(57) **CLAIM**

The ornamental design for a helmet padding system, as shown and described.

DESCRIPTION

FIG. 1 is a perspective view from above and behind a third embodiment of the helmet padding system;

FIG. 2 is a perspective view from below and in front of the helmet padding system of FIG. 1;

FIG. 3 is a rear view of the helmet padding system of FIG. 1;

FIG. 4 is a side view of the right side of the helmet padding system of FIG. 1, the left side being a mirror image thereof;

FIG. 5 is a front view of the helmet padding system of FIG. 1;

FIG. 6 is a top view of the helmet padding system of FIG. 1;

FIG. 7 is a bottom view of the helmet padding system of FIG. 1; and,

FIG. 8 is an exploded perspective view from above and behind the helmet padding system of FIG. 1.

The portions of the helmet padding system shown in broken lines depict environmental subject matter only and form no part of the claimed design.

1 Claim, 8 Drawing Sheets
